UNITED STATES PATENT OFFICE

LUTHER E. COHOON, OF LA GRANGE, ILLINOIS

FLUSHING APPARATUS

Application filed July 30, 1928. Serial No. 296,150.

This invention relates to improvements in flushing apparatus and it consists of the materials hereinafter described and more particularly pointed out in the appended claim.

5 The primary object of the invention is to provide a simple and efficient apparatus which operates on any water pressure for flushing a toilet.

Another object of the invention is to provide an apparatus which includes a reservoir and a valve which is normally secured in place by the water pressure and which may be dislodged from its seat and will float until all water has been discharged from the reservoir when the valve will automatically return to its seat and be held thereon by said pressure until the reservoir is again refilled.

These objects of the invention as well as others together with the many advantages 20 thereof will more fully appear as I proceed with my specification.

In the drawing:

Fig. 1 is a vertical sectional view through one form of my improved flushing apparatus 25 as when embodied in a building wall.

Fig. 2 is a similar view with the parts in a different position.

Fig. 3 is a transverse horizontal sectional view as taken on the line 3-3 of Fig. 1.

30 Fig. 4 is a vertical detail sectional view as taken on the line 4-4 of Fig. 1.

Referring now in detail to that embodiment of the invention illustrated in the accompanying drawings, the apparatus includes a reservoir or casing 1 which is closed at its top end by a wall 2 and is exteriorly threaded at its bottom end. In one side of the upright wall of the reservoir is provided an interiorly threaded annular flange 3 of 40 large diameter which is normally closed by a plug 4, a gasket 5 being interposed between said flange and plug to make a tight connection therebetween.

Threaded onto the bottom end of said casing is a cap like fitting 6 which includes an axially disposed depending tubular neck 7. To this neck is secured an elbow 7^a which opens laterally through the building wall 8 to receive the usual fittings (not shown) to 50 connect the same with the flushing rim of a

toilet bowl. Said cap like fitting includes a horizontally disposed wall 6^a in which is formed an outlet opening of substantially large diameter which is defined by a valve seat 9. Said opening is disposed axially of the top portion of the neck 7 and a valve member 10 within the reservoir and in the form of a sphere is adapted to engage upon said seat. Preferably said valve member is in the form of a hollow metallic ball 11 and may or may not be provided with a covering 12 of rubber or the like.

Depending from the wall 6^a to the rear of the neck 7 is a flange 13 into which a pipe 14 leading from a water service main is threaded to provide the water inlet for said reservoir.

On the front side of the top portion of the neck 7 is provided a tubular extension 15 the outer end of which terminates in a plane slightly forward of that of the reservoir flange 3. On said extension is screwed a nut 16. In said extension is an axially disposed actuating stem 17 the inner end of which opens into the neck 7 and on the outer end of said stem is a flat head 18 of substantially large diameter. A compressible packing 19 surrounds the stem between the neck 7 and a washer 20 on said stem and a helical expansion spring 21 surrounds said stem between the said washer and head 18.

The inner end of the stem is adapted to engage with the depending arm 22 of a bell crank like lever 23 which is pivoted on a horizontally disposed pin 24 within said neck. The horizontally disposed arm 25 of said lever is overweighted and includes a hump 26 which is disposed closer to the pin 24 than is the point of engagement of the stem with the lever arm 22. The other end of said lever arm 25 is depressed or cut away so that when the lever is actuated the hump 26 first engages the ball valve and then the outer end of said arm next engages the same.

27 indicates a handle member which projects through an opening in the nut 16 and has a flat circular head 28 which is disposed between the flat end of said nut and the flat head of the valve stem.

Assume that the apparatus is installed in

place in a building wall 8 forming one of the walls of a bath room or the like, and the elbow 7^a is connected up to the flush rim of a toilet bowl. With the parts in this position only the plug 4 and handle 27 together with the nut 16 and a small portion of the neck 15 is exposed. Assume also that water has entered the reservoir through the pipe 14 up to the level shown as permitted by the pocket of air at the top of the reservoir. This water of course is under pressure and the ball valve is held down against the seat thereby.

Manual pressure in any direction upon the handle 27 to tilt the same out of its normal position will by reason of its flat head, force the stem 17 inwardly against the action of spring 21 so that the inner end thereof will engage the arm 22 of the lever 23. This will cause the hump 26 of said lever to engage the ball and impart the initial lift thereto off its seat against the action of the water pressure tending to hold the same thereon. Because of the difference in actual length of lever arms at this time, said initial opening 25 is made easy and thereafter the outer end of the arm 23 imparts the final lift to the ball valve to free it absolutely from its seat. Water rushes under the ball into the neck 7 so that 30 the water pressure is immediately relieved when the ball will float to the top of the water, the level of which, of course, recedes as the water discharges, the valve bobbing about in the water.

35 When the reservoir is about empty the final discharge of the water will carry the ball to its seat and as the water is running into the reservoir during the discharge, it will soon build up to that level wherein pressure 40 will hold the valve against the seat, the ball valve always presenting a new contact surface to said seat for each operation. No matter at what pressure the incoming water may be, it is sufficient to do the work and 45 therefore the apparatus may be used in those vicinities where other automatic valves are inoperative because of either too high or too low water pressures.

Should it ever be necessary to inspect the 50 condition of the ball valve, this may be done by first shutting off the water main and flushing the apparatus. Thereafter the plug 4 may be removed to permit access to the interior of the reservoir and the ball may be replaced 55 by a new one if its condition so warrants and the plug then replaced.

By turning the nut 16 in one direction or the other the tension on the spring 21 may be easily determined and said spring acts at 60 all times to keep the stuffing box tight so that there is no leakage at the inner end of the stem 17 during flushing.

The apparatus consists of but a few parts which are easily made and assembled and 65 does not include minute parts which require

constant adjustment to insure operation. The apparatus is not dependent for operation upon any particular pressure but will operate efficiently on any pressure whether the same is high or low.

While in describing my invention I have referred in detail to the form, construction and arrangement of parts, I do not wish to be limited thereto except as may be specifically set forth in the appended claim.

I claim as my invention:

In an apparatus of the kind described a reservoir casing, a discharge member fixed to one end thereof and including a valve seat and a lateral tubular extension, a floatable ball in said reservoir adapted to engage upon said seat, a spring pressed stem and stuffing box in said lateral extension with one end of said stem opening into said discharge member, a lever mounted in said extension and including a handle outside the same for actuating said stem, and a bell crank lever in said discharge member and including a load arm to engage said ball and a power arm disposed in a position to be engaged by 90 said stem.

In testimony whereof, I have hereunto set my hand, this 19th day of July, 1928.

LUTHER E. COHOON.
